MEAT PACK

Filed July 12, 1929

INVENTOR,

Herbert Rumsey, Jr.

BY

John Rumsey,

ATTORNEY.

UNITED STATES PATENT OFFICE

HERBERT RUMSEY, JR., OF NUTLEY, NEW JERSEY

MEAT PACK

Application filed July 12, 1929. Serial No. 377,722.

The object of this invention is to provide a pack in which the contained substance shall be protected from exposure to the air, require the least amount of handling in the forming 5 of the pack, and be divided in sections or preformed cakes or patties so that when the substance is sausage or other minced meat, for instance, it will not be necessary to handle it in the molding or shaping preparatory 10 to cooking or other use thereof. The contained part or filler of the improved pack is characterized by cakes or masses of the substance and a piece of flexible sheet material, as paper, bent in zig-zag fashion and 15 thus forming pockets or recesses in which such cakes are arranged. This in itself is not new. The novelty in the present invention resides in providing the filler with a certain protective covering and the manner 20 in which the filler is assembled with the carton or container.

In the drawings,

Fig. 1 is a side elevation of the improved pack, showing the container opened at one 25 end and the piece of sheet material partially withdrawn in the act of withdrawing one of the cakes;

Fig. 2 is a right-hand end elevation thereof;

Fig. 3 is a perspective view of the filler before completion by application of a certain 30 protecting strip;

Fig. 4 is a perspective view of the completed filler;

Fig. 5 is a perspective view of the filler and container after the filler has been introduced 35 into the container;

Fig. 6 is a fragmentary perspective view 40 showing how the filler and container are interlocked; and

Fig. 7 is a view of the blank from which the said strip is formed.

Referring to Fig. 3, let 1 designate cakes 45 or sections of the minced meat or other substance and 2 the piece of flexible sheet material, as paper, bent zig-zag fashion and having said cakes or sections contained in pockets or recesses 3 formed by such bending thereof. The pockets are each open, or have 50 what I term mouths, opposite their respec-

tive bends, or in Fig. 3 at the top, and each is also open at what I term its sides (or in both directions lengthwise of the lines of the bending), so that the masses or cakes of said substance, which if minced meat or the like 55 will usually be sticky, are exposed at such mouths and sides. In the example only the alternate intervals between the walls of the material 2 formed by the zig-zag bending are formed as said pockets, as shown, so that the pocket mouths exist only at one side (the upper side in Fig. 3) and not the opposite side 60 of the body comprising the said masses 1 and bent sheet 2 and said masses are exposed at the first side and not at said opposite sides; this is not indispensable, but it is preferred 65 in view of the manner to be described in which the one-by-one delivery of the masses is preferably effected.

As so far described the masses 1 forming 70 portions of the mentioned body are exposed at three sides thereof. I aim to protect said body against the handling incident to completing the packaging, with malformation of 75 the masses and the adherence thereof to the hands especially if they consist of meat or the like sticky and/or plastic substance, and hence treat it as follows:

The piece 2 is provided with an extension 80 4 (which may be an integral portion thereof), and this is made to reach over the mouths of the pockets, so as to cover the masses where they are exposed by them, being brought face to face with the masses so 85 as to adhere thereto if they are sticky.

Further, to cover the sides of the pockets I provide a strip 5, the blank of which is shown in Fig. 7. This strip is bent around the said body so that its end portions cover 90 said sides, being also brought face to face with the masses so as to adhere thereto if they are sticky and in that way preferably secured to said body; it is (for a reason to appear) bent around said body in such manner that its mid-portion opposes that one of 95 the end masses in the series or succession thereof from which the extension 4 of the piece 2 reaches.

The result of the foregoing is to produce 100 what I term a filler adapted to be readily

entered into a carton or equivalent container of tubular form, such as the tubular carton 6 shown in Figs. 1, 5 and 6. This filler is entered into the carton from one end thereof so that the free ends of the extension 4 of piece 2 and of the strip are leading. The user is to withdraw the cakes or masses 1 one by one, and this is done by first opening the end wall 7 at what I term the mouth of the carton and then drawing upon the said leading end of the piece 2 so that each mass or cake will be discharged in the manner illustrated by Fig. 1. (Said leading end of piece 2 may be provided with a short extension 2a affording a convenient initial finger hold.) If only the alternate intervals between walls of the material 2 formed by the bending are utilized as pockets, each mass in discharging will do so with its bottom side leading.

20 In order to prevent the filler from being withdrawn in this operation, due to adhesion between each cake or mass and the covering here formed by the parts 2-4 and 6, the filler is secured in the carton by an interlock 25 formed between them, say as follows:

The end of the carton into which the filler is entered has a flap 8 (preferably two such flaps, opposite each other and also another or closing flap 9). The mid-portion of the strip 30 has a lateral flap 10 (preferably two such flaps, opposite each other). When the filler is fully entered the flaps 8 of the carton are first folded over the end of the filler, then the flaps 10 of the filler are folded over the flaps 35 8, and finally the cover flap 9 is made to cover the flaps 8 and 10, it preferably having a tab 9a to enter the carton between its opposite wall and the filler. Thus the filler will be securely locked against withdrawal and the 40 withdrawal of the masses one by one may be effected without disturbing the parts 2-4 and 6 or more than the single mass intended.

The piece of material 5 is preferably stiff, as card-board. Thus its end portions form 45 walls which adhere to the sides of the cakes, facilitate the entry of the filler into the carton and prevent malformation of the masses in the handling both incident to that operation and of the completed pack.

50 Having thus fully described my invention what I claim is:

1. An article of manufacture comprising a piece of sheet material bent zig-zag and thereby forming a succession of pockets, each 55 pocket having an open mouth opposite the corresponding bend in the piece and masses of adhesive substance to be packed occupying the respective pockets, said piece having an extension reaching over said mouths and 60 adhering to said masses, in combination with a container surrounding and closely embracing the succession of pockets from end to end and having its end at the free end of said extension open, whereby said masses are successively removable at said end of the con-

tainer by drawing upon the end of the said piece adjoining the same.

2. An article of manufacture comprising a piece of sheet material bent zig-zag and thereby forming a succession of pockets, each 70 pocket being open at both sides, masses of the adhesive substance to be packed occupying the respective pockets, and a strip of sheet material bent around one end of the body formed by said piece and masses and having 75 its end portions covering the pockets at both said sides of each of them, in combination with a container surrounding and closely embracing the article from end to end of the succession of pockets and having its end at 80 the other end of said body open, whereby said masses are successively removable at said end of the container by drawing upon the end of said piece adjoining the same.

3. In combination, a tubular carton and a 85 filler therein comprising, with the substance to be packed adapted to be withdrawn from one end of the carton, a covering of sheet material for said substance adhering thereto and having an interlock with the carton 90 opposing withdrawal from the latter of said covering with said substance.

4. In combination, a tubular carton having a flap at one end and a filler in the carton comprising, with the substance to be packed 95 adapted to be withdrawn from the other end of the carton, a covering of sheet material for said substance having a flap overlapping the first flap exteriorly thereof and thus opposing withdrawal from the carton of the 100 covering with said substance.

5. An article of manufacture comprising a piece of sheet material bent zig-zag and thereby forming a succession of pockets, and masses of adhesive substance to be packed 105 occupying the respective pockets, in combination with a container surrounding and closely embracing the succession of pockets from end to end and having its end at one end of said succession of pockets open, whereby said masses are successively removable at 110 said end of the container by drawing upon the adjoining end of the piece.

6. A filler comprising a succession of masses of adhesive substance and a covering 115 of sheet material adhering to the masses and including a piece of sheet material bent zig-zag and thereby forming a succession of pockets occupied by said masses, in combination with a container surrounding and 120 closely embracing the filler from end to end and having said covering attached thereto at one end of the filler and being open at the other end of the filler, whereby such masses are successively removable at the latter end 125 of the container by drawing upon the adjoining end of the piece.

In testimony whereof I affix my signature,
HERBERT RUMSEY, JR.
